G. C. BEIDLER,
METHOD OF AND DEVICE FOR DEVELOPING FILMS,
APPLICATION FILED MAR. 23, 1916.
1,346,780. Patented July 13, 1920.

UNITED STATES PATENT OFFICE.

GEORGE C. BEIDLER, OF ROCHESTER, NEW YORK.

METHOD OF AND DEVICE FOR DEVELOPING FILMS.

1,346,780.

Specification of Letters Patent. Patented July 13, 1920.

Application filed March 23, 1916. Serial No. 86,210.

To all whom it may concern:

Be it known that I, GEORGE C. BEIDLER, a citizen of the United States of America, and resident of Rochester, in the county of 5 Monroe and State of New York, have invented certain new and useful Improvements in Methods of and Devices for Developing Films, of which the following is a specification.

10 This invention relates to photography and particularly to photographing apparatus in which provision is made for developing the sensitized medium, as in photographing and developing apparatus, or in developing apparatus.

15 This invention is of special importance and advantage in subjecting the film to the action of fluid for developing it or in connection with the developing process, and particularly for treating lengths of film which are practically coextensive in area with the field of exposure or the surface exposed.

20 While it is not my purpose to be limited with respect to the use of the invention, an example of its utility may be mentioned as when it is associated with or made a part 25 of means for exposing film to light and means to sever the film which has been exposed, from a web or roll of film, and which, previous to the cutting operation has been 30 drawn from an exposing chamber, for delivery to the means for developing the film.

35 An object of the invention is to provide novel means for holding, supporting or suspending the film in a liquid adapted to act on its coated surface, as when the film is developed, whereby the said coated surface may be accessible and the liquid may uniformly cover the coated surface; furthermore 40 to provide a holding device which will retain the film to prevent one part of the coated surface from contacting another part of such coated surface, yet accomplishing the result within a comparatively small receptacle requiring but a small quantity of 45 fluid for the submergence of the portion of the film that has been exposed to light.

50 With the foregoing and other objects in view, the invention consists in the method of subjecting film to the action of fluid; as well as the apparatus.

In describing the invention in detail, reference will be had to the accompanying drawing forming part of this specification,

wherein like characters denote corresponding parts in the several views and in which—

Figure 1 illustrates a view in perspective of a receptacle with a film holding means embodying one example of the invention, the view being partly in section;

Fig. 2 illustrates a longitudinal sectional view of said parts;

Fig. 3 illustrates a transverse sectional view of the receptacle and film holder with conventional illustrations of cutting devices 65 and film feeding rolls;

Fig. 4 illustrates a sectional view of a fragment of the receptacle;

Fig. 5 illustrates a sectional view of a fragment of the receptacle and a fragment 70 of film therein;

Fig. 6 illustrates a fragment of the receptacle omitting the film and showing the cover of the receptacle in a different position as compared with its position in Fig. 5;

Figs. 7, 8 and 9 each illustrate a fragment 75 of a film holder or suspending means embodying a modification; and

Fig. 10 illustrates the feeding mechanism by which film may be delivered to the receptacle.

In that form of the invention illustrated a receptacle 10 for holding a liquid, preferably developer, is placed in position to receive film 11 which may be fed or delivered 85 to it by rolls 12 and 13 and after the film has been delivered to the receptacle it may be cut as by knives 14 and 15. The rolls 12 and 13 operate in conjunction and one of them is turned in any suitable manner as by 90 a crank handle 12a.

The film is preferably delivered to the receptacle 10 edgewise, and for the purpose of preventing evaporation of the liquid and to exclude light the receptacle may have a 95 cover 16 with a slot 17 through which the film may enter the receptacle; furthermore, the cover may have its ends turned under as shown at 18, to embrace flanges 19, which project from the ends of the receptacle, to establish a sliding and guiding connection between the cover and receptacle.

The film holding or suspending element in the form of the invention illustrated, comprises an apron like structure constituting 100 a guide, and as illustrated in Figs. 1, 2 and 3 it consists of a metallic plate of a material which will not be injuriously affected by

developing fluids, the said plate having a comparatively straight guiding portion 20 lying against the inner surface of one wall of the receptacle and terminating in a hook 21 overlying the upper edge of the wall, which wall constitutes its support or suspending means. The remainder of the plate or sheet is curved in convolutions, as at 22 and 23, and spaced apart in order that film 10 may travel in the space and be guided by the curved plate. It will be observed that the film enters what may be termed the side of the convolutions of the holder rather than the end of the said holder.

15 By choice the back or uncoated surface of the film should be next to the apron or vertical portion of the plate as it enters the receptacle and when so introduced the coated surface of the film is not likely to come into contact with the plate and the fluid in the receptacle will more readily find its way to such coated surface uniformly, since the back of the film appears to follow and engage the surface of the plate as said film 25 travels the circuitous path outlined by said convolutions.

The suspending device may be held in the receptacle by the hooked end as in Fig. 1, or the hook may be omitted as shown in Fig. 6, and the plate or apron may be fastened in any appropriate way, as by brazing or the like directly to the side of the receptacle.

In operating to treat film, the said film is applied or delivered to the receptacle and as it travels in the receptacle it is guided by the convolutions of the curved supporting device and is loosely coiled in order that the liquid within the receptacle may reach the coated surface of the film. In the delivery of the film to the receptacle a small margin of film, which is the portion between the knife and the top of the receptacle, projects from the said receptacle and the film may be drawn from the receptacle in any desired manner. That is to say, it may be drawn mechanically, by means not shown, (as such mechanically operated drawing devices are a part of the prior art, such a device need not be shown herein) or the film may be manually drawn from the receptacle by grasping the projecting margin of the film and pulling it. The projecting end of the film may be flexed to render it more accessible, and one example of this operation is disclosed in Fig. 5, where the cover of the receptacle is slid outward so that the edge or wall of the slot of the cover engages the film and presses it against the edge of the 50 receptacle, thus bending or flexing the film beyond the side wall of the receptacle. The film can be pressed against the upper surface of the sliding cover and when said cover is moved outward, the film will be drawn 55 with it, but it is perhaps preferable to

grasp the film using the digits of the hand. In the relation of parts illustrated in Fig. 5, the liquid on the film will be displaced to a great extent, if the film is drawn from the receptacle by hand, as the film would then be in contact with the cover and with the stationary portion of the receptacle or supporting device.

To illustrate how it is possible to modify the construction of the suspending or supporting element, a few examples of the materials which may be employed are illustrated in Figs. 7, 8 and 9. In Fig. 7 there is shown a fragment of a plate 24, the said plate being perforated. In Fig. 8 a fragment of wire netting or screen 25 is shown, and such material may be used in making the element for supporting the film in the receptacle. Or, as shown in Fig. 9, a series of bars or rods may be bent in the shape 85 of the supporting element and these bars or rods may be attached to the receptacle.

I claim—

1. The method of subjecting film to developer consisting in pushing film into a developer container having a coil therein and causing the film to coil in a spiral form with spaces between the adjacent volutions of the coil.

2. The method of subjecting film to a developer consisting in pushing film into the side of a substantially coil form supporting member immersed in developer whereby the film travels in the space between the volutions of the member.

3. In a device relating to photography, a coil-form film holder having spaces between the volutions of the coil, means for pushing film into the holder whereby the film travels in the space between the volutions of the coil and follows the volutions of the coil.

4. In a device relating to photography, a film supporting device comprising a member having convolutions to receive film, a receptacle for containing the said member, and means for pushing the film edgewise into the side of the said member.

5. In a device relating to photography, a film supporting means having convolutions to receive and coil film when the film is pushed into the said supporting means, and a receptacle for containing said means.

6. In a device relating to photography, a film holding means having convolutions to guide and coil a film when the free advancing end of the film is delivered to it edgewise.

7. In a device relating to photography, a member having convolutions around which film may be coiled, and means externally of the said member for forcing film therein and causing it to follow the convolutions of the said member.

8. In a device relating to photography, means for delivering film edgewise to a

holder and a holder to receive the film and adapted to coil the film as said film travels into said holder.

9. In a device relating to photography, a film supporting means having convolutions to receive and coil a film when the film is pushed into said supporting means, a receptacle for containing said means, and a slotted

cover on the receptacle through which the film is delivered. ¹⁰

In testimony whereof, I affix my signature in the presence of two witnesses.

GEORGE C. BEIDLER.
